UNITED STATES PATENT OFFICE.

MARYAN L. LISOWSKI, OF CRANFORD, NEW JERSEY.

APPARATUS FOR FORMING CONCRETE FABRICS.

1,330,126.

Specification of Letters Patent.

Patented Feb. 10, 1920.

Application filed September 5, 1917. Serial No. 189,894.

To all whom it may concern:

Be it known that I, MARYAN L. LISOWSKI, a citizen of the United States, residing in Cranford, in the county of Union and State of New Jersey, have invented certain new and useful Improvements in Apparatus for Forming Concrete Fabrics, of which the following is a specification.

This invention relates to apparatus for use in the construction of buildings, columns, girders, floors and other fabrics, of plastic material and, particularly, has reference to apparatus having collapsible or knock-down characteristics capable of being shaped to any form desired and extended to any degree desired, and to have a variety of predetermined structural features of novelty.

Among the objects of my invention may be noted the following: to provide separable or collapsible and relatively adjustable forms adapted to the construction of beams, girders, floors, slabs, columns for buildings and other fabrics; to provide a combination of forms, braces and tying members capable of being adjusted and readily separated for knock-down purposes and adapted for the uses heretofore noted; to provide forms for plastic material which are simple in construction, strong, durable and effective in use to save time, material and labor in the construction of various fabrics, such as noted in the foregoing; to provide forms for plastic material, adapted for many uses, which are economical and capable of being quickly set up and knocked down and used for different forms of structures in the same building or fabric or in independent fabrics; to provide forms for plastic material adapted for the uses and purposes hereinbefore set forth which may be used over and over again and the parts of which may be quickly repaired and replaced without undue expense or delay; to provide improved means for connecting the various elements of the apparatus rendering said elements adjustable in different angular directions and capable of being quickly set up or built in the form desired to be given to the plastic material and quickly knocked down or stripped from the latter when it has become set; and to provide certain simple, economical, strong and durable features of construction of the various parts of the forms and connections enabling the latter to fulfil the objects set forth in the foregoing.

With the above objects in view and others which will be detailed during the course of this description, my invention consists in the parts, features, elements and combinations thereof hereinafter described and claimed.

In order that my invention may be clearly understood, I have provided drawings wherein:

Figure 1 is a sectional elevation of a fragment of forms and concrete construction, in this instance illustrating a floor of a building, and including the temporary supporting structure and forms made in accordance with my invention;

Fig. 2 is a side elevation of the left end of the structure of Fig. 1 looking at the casting from the right side thereof;

Fig. 3 is an enlarged sectional view substantially on the line 3—3 of Fig. 2;

Fig. 4 is a sectional view showing another form of my invention, the part illustrated being similar to that at the left end of Fig. 1;

Fig. 5 is an enlarged sectional view substantially on the line 5—5 of Fig. 4;

Fig. 6 is a side elevation of Fig. 7 looking at the latter from the right hand side, and illustrating another form of my invention adapted for the construction of angular pillars or columns;

Fig. 7 is a section substantially on the line 7—7 of Fig. 6;

Fig. 8 is an enlarged detail view of one corner or angle of Fig. 7;

Fig. 9 is a section substantially on the line 9—9 of Fig. 8;

Fig. 10 is a view similar to Fig. 6 showing another form of my invention wherein the column to be constructed is circular instead of angular, as in Figs. 6 and 7;

Fig. 11 is a section substantially on the line 11—11 of Fig. 10; and

Fig. 12 is an enlarged sectional detail also substantially on the line 11—11 of Fig. 10.

Referring to the drawings and, particularly, to Figs. 1 to 3, inclusive, a suitable supporting structure is built up between the suspension girders or I-beams, one of which is illustrated at the left of Fig. 1, said supporting structure comprising cross-beams or timbers 13, longitudinal beams or timbers 16 thereunder, and uprights or supports 17. On the cross-beams 13 are laid any number of loose boards 14 which may be desired or required; and upon said boards are laid

sheet iron plates or strips 15 upon which the plastic material is disposed, as required. The cross-beams or timbers 13 reach to within a short distance of the I-beams on 5 opposite sides thereof, and their ends are connected by channel irons 1 which constitute the supporting means for the form-plates 2 and 3, which are, respectively, connected to the outer sides of the channel 10 irons 1 by means of bolts or other removable devices. The form-plates 2 and 3 depend parallel with the adjacent I-beam and overlap the upright members of angular form-plates 5 and 4, the horizontal members of 15 which extend toward, and overlap, each other. Thus, a vertically extensible, as well as laterally extensible, form-casing is produced into which the plastic material is filled around the I-beam. To the bottom of 20 each of the channel irons is detachably bolted a depending brace-member 6, the same extending parallel with form-plates 2 and 3 and telescoping the U-shaped, in cross-section, brace-members 7 and 11, respectively. The member 7 has a flat extension 9, at a right-angle thereto telescoping the horizontal U-shaped, in cross-section, member 8 of the brace-member 11. The several members 6—7—8—9 and 6—11 are connected together detachably by means of 25 pins 10 passing through registering and corresponding apertures in the respective members, thus enabling the members 7 and 11 to be adjusted vertically on the members 6, 30 and the members 8 and 9 to be adjusted horizontally relatively, in order to correspond with the size and shape of the form-plates, as will be readily understood. To provide an auxiliary support for the form- 35 plates and brace-members, I employ U-shaped wires 12 which are bent around the I-beam and the lower, free ends of which are bent at an angle under the lower member 8 and upwardly parallel with the same, as 40 shown in Figs. 1 and 2, the same thus sustaining a goodly portion of the weight of the apparatus and relieving the connecting pins and bolts of undue strain. Along the length of the structure and of the I-beams, 45 viewing Fig. 2, it may be necessary to couple together a plurality of form-plates and brace-members, in order to carry out lengthy work. To accomplish this, I provide coupling bars 20 which may be detachably 50 bolted to one of the channel irons within the channel, as shown at the right of Fig. 2, and extended over into the channel of an adjacent channel iron behind one or more angular guide members 21, which are bolted 55 to the bottom of the channel iron with sufficient space between the same and the web of the channel iron to enable the bars 20 to slide freely, but be held snugly. By this means 60 more or less of endwise adjustment of the form-plates and brace-members can be ac-

complished. This form of my apparatus is particularly adap^l for floor construction and incasing the girders or I-beam supports.

In Figs. 4 and 5, I have shown another form of my invention wherein the transverse timbers 13, loose boards 14 and channel irons 1 are all similar to the corresponding features of Fig. 1. Likewise, in this figure, the auxiliary or supporting wires 12, the I-beam, and the form-plates 2, 3, 4 and 5 are the same as in Fig. 1. Instead of forming the brace-bars or members of flat metal, as in Fig. 1, I have shown the same as being formed of circular, telescopic members 22—23, 24—25, 26—27 and 28; that is to say, the member 22 is bolted or otherwise secured to the adjacent channel iron 1 and telescopes the tubular member 23, the latter two being adjustably connected together by pins 10 passing through corresponding apertures in the members. The member 24 is right-angular in form and telescopes the member 23 and also the member 25, connection and adjustment being provided for by pins 10 passing through 85 corresponding apertures in the parts. An angular member 26, similar to 24, telescopes the members 25 and 27, connection and adjustment being provided by pins 10 passing through apertures in the members. By this means adjustment in different angular directions can be made for increasing 90 both the width and the depth of the mold. In this form, I preferably apply between the form-plates, and the respective brace-members about the same, beams or boards 29 which act as additional stiffeners in case 95 the co^{operating} members are spaced too far apart. This gives stability to the forms and makes the apparatus very rigid. In either form of my invention the mold frame is composed of the members indicated by the 100 reference numerals 2 to 11, inclusive, Figs. 1 to 3, inclusive, or the equivalent members in Figs. 4 and 5, coupled with brace-boards 29 in the latter figures; and the horizontal members of the mold frame provide a platform for the members 4 and 5, and the boards 29.

In Figs. 6 to 9, inclusive, I have shown another form of my invention whereby I may form angular columns or beams, either 105 with or without interior stiffeners, such as the V-shaped central I-beam members, which, as shown, are bent longitudinally and placed with their vertices together. About these central stiffeners I apply my 110 form-plates 38 and 39, 40 and 41, which are right-angular in cross-section and the members of which overlap each other, whereby 115 to provide for extensibility in two different angular directions. At the angles of the 120

form-plates, I provide Y-shaped stiffening beams or braces, the prongs of which substantially parallel the respective form-plates, and the webs 30 of which extend 5 tangential to the angles of the form-plates. In this instance of my invention, the brace-members indicated at 31 and 32, and which pass through apertures in the webs 30, are circular in form and are disposed at the angles 10 of the frame or mold. At opposite ends, the said members 31 and 32 telescope tubular members 33, apertures being provided in the several members through which pins 10 may pass, as in the other 15 forms of my invention, for holding the parts together and providing for adjustment in the different angular directions. Strengthening boards or beams 29, the same as in Fig. 4, are provided between the 20 form-plates and brace-members for the purposes indicated in the foregoing in connection with the Fig. 4 form of my invention. Longitudinal extensibility of the corner brace-members is provided for by 25 the coupling bars 34, Fig. 6, which are U-shaped in cross-section and which embrace the webs 30 of said brace members, being coupled thereto at opposite ends by bolts or pins, as heretofore explained in connection 30 with Fig. 2. It will thus be seen that columns, pillars and beams of angular form 35 can be produced from plastic material through the medium of my apparatus with great facility and economy of time and labor, and that the apparatus can be quickly set up and knocked down or stripped from the plastic material when it has become set.

In Figs. 10, 11 and 12, I have shown a 40 form of my invention capable of producing circular columns, pillars and beams, and therein the several form-plates 36 are made in the form of segments of a circle and of such width as to enable them to be overlapped for contraction and expansion in the 45 same manner as described with reference to the other forms. At the center of each of the form-plates, I provide longitudinal braces which are substantially T-shaped in 50 cross-section, the webs 35 of which are provided with slots or apertures, as shown in Fig. 10, through which pass the brace-members 37 which encircle the form-plates, and, at their ends, overlap and are adjustably 55 connected together by means of apertures and pins or bolts, as heretofore explained. The heads of the brace-members, or those portions extending at a right-angle to the webs 35, conform more or less to the 60 form-plates 36 and operate to effectively brace the same and hold them in place. With this form of my invention, it will be readily understood that I can make a pillar or column form of substantially any desired 65 diameter. Longitudinally of the

structure, the webs 35 should be coupled and adjustably connected through the medium of U-shaped bars 34, as indicated in connection with Fig. 6.

From the foregoing detail description, the mode of operation will be readily understood; that is to say, structural supports, such as 17, 16, 13, 14 and 15 will be set up between girders or beams if a flooring is to be laid in buildings, and the channel irons 1 will be set in place as described. Then the supporting loops 12 will be laid over the I-beams and the form-plates properly adjusted, whereupon the brace-members 6, 7 and 11 will be set in place and 75 properly adjusted. The cement may now be poured or shoveled in and allowed to set. In forming a column, post or beam of angular form, such as shown in Figs. 6 and 7, the structural iron cores, whatever they 80 may be, will be surrounded with the form-plates 38, 39, 40 and 41, boards 29 set in place, if it be desired to use the same, and then the corner brace-members set up and surrounding brace-members applied, as will 85 be readily understood, adjustments being made of the various form and brace-members to accord with the size of structure desired. The plastic material will then be poured in, as shown. The same procedure 90 will take place with reference to the apparatus shown in Figs. 10 and 11, in all instances longitudinal adjustments of the 95 brace-members being accomplished through the medium of the coupling bars 20 or 34, as 100 the case may be. It will be seen from the structure and mode of operation described that, when the plastic material is poured into the forms or molds, the latter will be forced downwardly or expanded to their 105 proper positions under the limitations imposed by the brace-members of the apparatus, it being understood that the form-plates have no mechanical connection but overlap each other loosely. Economy of 110 time, labor and material are direct results of the use of my structures, which latter comprises the automatically adjustable or extensible form-plates which are braced and firmly held within predetermined 115 limits by the brace-members, and which latter may be adjusted in different angular directions to increase or decrease the size of the form and the structure to be produced therefrom. The apparatus is also adjustable 120 for differences in distances between girders, uprights and length of girders; and any shape of column, beam, and any kind of straightaway or angular structures 125 can be produced by the use of my apparatus.

Having thus described my invention, what I claim and desire to secure by Letters Patent is:

1. In apparatus for the purpose set forth, 130

primary supporting means; primary form-plates secured to said supporting means and secondary form-plates arranged in overlapping relation to the primary form-plates and to each other; primary brace-members secured to said supporting means and secondary brace-members arranged in overlapping relation to the primary members and to each other, the brace-members being arranged to surround the form members; and means for adjustably connecting the brace-members so as to predetermine the size of the form and firmly support the latter.

2. In combination with a fabric girder or support which is to be surrounded or incased with plastic material, primary supporting means, primary form-plates secured to said supporting means and secondary form-plates arranged in overlapping relation to the primary form-plates and to each other; primary brace-members secured to said supporting means and secondary brace-members arranged in overlapping relation to the primary members and to each other, the brace-members being arranged to surround the form members; means for adjustably connecting the brace-members so as to predetermine the size of the form and firmly support the latter; and auxiliary supporting means connected to said girder and coöperating with the brace-members to aid in the support of the latter.

3. In apparatus for the purpose set forth, primary supporting means; form bracing means secured to said supporting means, comprising members adjustable relatively in two different angular directions; form-plates supported by said primary supporting means and said bracing means and within the latter, said form-plates being automatically expansible in one direction to adapt themselves to the inside dimensions of the bracing means.

4. In apparatus for the purpose set forth, form bracing means comprising a plurality of members adjustably connected together; means enabling the bracing members to be adjusted relatively in several different angular directions; form-plates supported by said bracing means and inclosed by the latter, said form-plates being automatically movable relatively to each other in different angular directions whereby to adapt themselves to the inside dimensions of the bracing means.

5. In apparatus for the purpose set forth, primary supporting means; form bracing means secured to said supporting means; form-plates supported by the bracing means and held in position by the latter; and additional bracing means coöperating with the form-plates to sustain the latter at points not engaged by the said form-bracing means.

6. In apparatus for the purpose set forth, primary supporting means; form bracing

means secured to said supporting means; form-plates supported by the bracing means and held in position by the latter; and additional bracing means coöperating with the form-plates to sustain the latter at points not engaged by the said form-bracing means, said additional means extending at an angle to the form bracing means.

7. In combination with a plurality of primary supporting means each of predetermined length and arranged in alinement; coupling bars between adjacent ends of the alined supporting means; means for adjustably securing the coupling bars to the coupled members of the primary supporting means; form-plates secured to the primary supporting means and brace-members surrounding the form-plates; and means for securing the bracing means to the primary supporting means.

8. In combination with form-plates having predetermined shaping characteristics for the plastic material and arranged in overlapping relation; means surrounding the form-plates for bracing and supporting the same, including means whereby the bracing means may be adjusted in several angular directions, the overlapping form-plates being adapted to expand or contract automatically when the bracing means are adjusted.

9. In combination, a plurality of form-plates arranged in predetermined relation to shape the plastic material; bracing means comprising a plurality of independent members adapted to coöperate with the form-plates to hold the same in predetermined relation, said bracing means extending about the form-plates at an angle to the length of the latter; means by which the members of the bracing means may be adjusted relatively in different angular directions; and, supporting means for the bracing means extending at an angle to the latter.

10. In apparatus for the purpose set forth, a plurality of form-plates shaped to give the desired form to the plastic material, said form-plates being adapted to be arranged in overlapping relation; a plurality of similar separable brace-members adapted to encircle the form-plates; means for detachably connecting the brace-members, the structure being such that the brace-members are interchangeable and quickly set up and knocked down.

11. In apparatus for the purpose set forth, a plurality of form plates shaped to give the desired form to the plastic material and adapted to provide a maximum and a minimum size of form and to be arranged with their members in overlapping relation; a plurality of similar separable brace members adapted to encircle the form plates; and means for adjustably securing the brace members together so as to correspond with

the size of form made by the form plates, and including means for detachably connecting the brace members, the structure being such that the brace members are interlocking such that the brace members are interlocking 5 changeable and quickly set up or knocked down.

12. In apparatus for the purpose set forth, a frame forming part of a mold to shape concrete about a beam or girder in a fabricated structure, said frame having a platform to support a brace board of the form and two members at an angle to said platform; a pair of members parallel with the frame members; means for adjusting the frame members relatively to the parallel members; and means for suspending said frame beneath the beam or girder.

13. In apparatus for the purpose set forth, a pair of oppositely supported channel irons; a plurality of form members shaped to give the desired form to the plastic material, said form members each having a platform and members at an angle to said platform; members co-operatively connected 25 with the form members and supported from the channel irons; side wall members supported on the form; and means for suspending said form members beneath the beam or girder.

14. Apparatus for the purpose described comprising a U-shaped brace member; the base of which is flattened and the arms of which are provided with a plurality of apertures; angle-members adjustably secured to 35 said arms through the medium of said ap-

tures; form-plates adapted to be supported between the arms of said brace member; form members adapted to be supported upon the flattened base of said brace member; and means whereby the entire structure may be secured to a beam or girder.

15. In apparatus for use in a system of concrete construction, the combination of a plurality of column beams arranged relatively to produce the core of the form desired; relatively adjustable angular means spanning the space between the beams and closing the sides thereof, regardless of the size of the form, within predetermined limits; brace members, and means for securing them about the structure; and angle-irons secured to the several brace members at the angles of the spanning means and adapted to coöperate with the latter.

16. In apparatus for use in a system of concrete construction, the combination of a plurality of column beams arranged relatively to produce the form desired; automatically adjustable means for closing the spaces between the beams, regardless of the size of the form, within predetermined limits; brace members applied to the foregoing structure including means for securing them adjustably together and upon said structure; angular members adapted to be applied to 65 the several corners of the structure; and means for securing said angular members in place.

M. L. LISOWSKI.
